FLUE-GAS-RECIRCULATING SYSTEM FOR CRACKING-STILL OPERATIONS.

Application filed May 9, 1927. Serial No. 189,959.

The present invention pertains to oil cracking operations, and particularly to that phase of such operations which relates to the maintenance of the proper heat conditions at the 5 heating surfaces of the cracking units.

Accordingly the principal object of the invention is to provide a more efficient as well as more economical system, in which a more uniform temperature and practical control 10 of the same are rendered possible by a recirculation of a portion of the flue gases in a peculiar and effective manner through the combustion chamber of the furnace.

It is furthermore an object of the invention to devise not only a method but an improved apparatus of such a character as to improve generally the cracking still operation for which the system is especially adapted.

With these general objects in view, the invention will now be described by reference to the accompanying drawings illustrating one form of furnace and still construction adapted for the embodiment of my improved 25 system, after which those features and combinations deemed to be novel will be particularly set forth and claimed.

In the drawings:

Figure 1 is a vertical sectional elevation illustrating a burner and cracking still construction embodying the system herein described; and

Figures 2 and 3 are horizontal and vertical sectional views, representing sections 35 taken on the lines II—II and III—III respectively, of Figure 1.

In the drawings is illustrated one commercial form of cracking still unit comprising a tube bank 4 mounted between drum tube 40 headers 5 and spanning the upper portion of the furnace combustion chamber A, the drum tube headers being in turn connected to a horizontal upper drum 6, as clearly shown in Figure 1. This form of cracking unit as 45 well as the type of furnace construction shown are merely for illustrative purposes, as it is to be understood that the invention is equally well adapted for other forms and arrangements of cracking stills and other 50 types of furnaces, either with or without the dutch oven forming an extension 7 from the lower portion of the furnace combustion or fire chamber A.

In all oil cracking processes the operating temperature at the still heating surfaces must 55 be kept within a given limit, viz, not over fifteen to sixteen hundred degrees Fahrenheit, which is in contrast to ordinary boiler operation where the temperature in the combustion chamber frequently reaches three 60 thousand degrees Fahrenheit, the only limits under such conditions being the temperatures to which the refractory linings may be subjected without excessive maintenance expense, and the attempt is also made to reduce 65 as far as possible the temperature of the flue gases as they leave the boiler heating surface in order to keep down the loss of heat up the stack.

Now since the temperature limit for the 70 cracking operation must not exceed fifteen to sixteen hundred degrees Fahrenheit, which is much lower than that produced by the efficient combustion of most fuels, it has always been necessary to reduce materially the 75 temperature of the combustion gases, usually by admitting excess air into the combustion chamber at such a rate as will produce a volume sufficient for this cooling function. At the outlet from the combustion chamber 80 into the flues a restriction as to temperature also exists since this must not fall below eight hundred to eleven hundred degrees Fahrenheit if an efficient cracking temperature is maintained. Being thus limited to a 85 relatively low initial combustion temperature, it is impossible to effect a very great interchange of heat by radiation, and to accomplish this it becomes necessary to make the heat transfer principally by convection. Various methods and complex structures have 90 been devised for this purpose, some even providing a separate room or chamber for the still unit, but all such expedients are open to the same general economical objection as regards too great a loss of heat to the stack on account of the great volumes of gas leaving, the cracking unit at comparatively high temperatures.

It is apparent that these temperature reduction requirements which have heretofore been met by providing excess air could be met just as satisfactorily by substituting any other suitable gas inasmuch as the oxygen for supporting the fuel combustion is not derived 105 from this excess air supply. Hence a cooling

diluent composed for the most part of nitrogen and carbon dioxide may be employed just as efficiently for the same purpose, while air is admitted in volumes sufficient merely for 5 furnishing the oxygen required for burning the fuel.

This is the principle followed in the present invention, as practiced by the apparatus illustrated in the drawings where the flue 10 gases, after leaving the space occupied by the tube bank 4, are discharged through suitable exit openings 8 into the flue passage or conduit 9, as many of which are provided as may be necessary, for conducting the gases 15 to the stack 10. In the present instance, however, a fraction of these gases is diverted for recirculating purposes into one or more branch conduits 12 by the action of a suction fan 14 in communication with said branch 20 conduits, and leading off from the latter are separate branch passages 15 and 16 communicating with gas intake compartments 17 and 18 at the top and bottom, respectively, of the oven extension 7, as clearly shown in Figure 1. By proper control, by means of dampers 19' in the passages 9 and 12 and similar dampers 19 and 19' in the passages 15 and 16, respectively, the correct and desired amount of flue gases can be recirculated and 30 the balance of the waste gases rejected and delivered to the stack 10. A marked saving of fuel is effected by this method of recirculation, for it is readily seen that the diluting gas is required to be heated up in the combustion 35 chamber only from a temperature ranging from eight hundred to eleven hundred degrees, in contrast to the increase in temperature required to be imparted to air entering at atmospheric temperature.

40 The mere discharge of the recirculated flue gas into the combustion chamber, without other regulations, will not accomplish the most efficient results, as it is necessary to effect a thorough mixing and practically uniform distribution of the gases in the combustion chamber in order to secure as even and 45 uniform temperatures as possible. Since the temperature of the gases resulting from the fuel combustion greatly exceeds that of the recirculated flue gases, and there is a corresponding difference in density and hence a tendency to travel in separate strata instead of mixing or diffusing, the problem of thoroughly mixing the two and to do this without 50 at the same time lowering the temperature of the flame body to such an extent as to interfere with complete combustion, presents some real difficulties.

55 In the drawings I show a double burner arrangement,—the number of burners 20 or the method of firing itself being of course entirely optional. These burners are illustrated as located in a central burner compartment 22 between the compartments 17 and 18, from 60 which it is separated by refractory partitions,

the upper one being in the form of arches 23 and the lower one taking the form of a shelf 24, preferably projecting somewhat further into the combustion chamber A than the arches 23. All the air required for combustion is admitted into the burner chamber 22. By this means the flue gases are discharged into the combustion chamber from the compartments 17 and 18, in relatively thin sheets or streams between the fuel burning zone 75 and two other sources of heat, viz, the refractory linings of the top and bottom walls of the combustion chamber. In this connection it will be recognized that the absorption of heat by these refractory linings is mainly by 80 radiation from the combustion zone, and such radiation takes place without any appreciable heating effect upon the gases, while very little loss of heat occurs by conduction through the walls. The floor and arches of 85 the combustion chamber are also maintained at a high temperature by the absorption of heat from the burning fuel, and hence it is apparent that the construction of these several chambers or compartments is such as to 90 quickly and effectively heat not only the combustion gases travelling through the burner compartments but also the two thin streams of recirculated flue gases by the principle of convection as they flow past and in contact 95 with these hot wall surfaces; and by the time the combustion gases have travelled through and out of the burner chamber or compartment their temperature has reached such a point that any heat loss to the recirculated flue gases will be insufficient to interfere with complete combustion. These two comparatively thin streams or sheets of recirculated gases also permit more intimate contact between the recirculated gas and the combustion 100 gas, which results both in a more complete intermixing of the gases and also in a more rapid rise in the temperature of the flue gas, so that the ultimate result is a homogeneous mixture of the gases at a fairly uniform 105 temperature ready for passage into the zone occupied by the heating surfaces of the cracking still units.

In practice, I prefer under some conditions to employ a checker wall structure 26 at the discharge points between the compartments 17 and 18 and the combustion chamber A. As illustrated in Figure 3, the openings 27 in these walls are so constructed and arranged as to interpose a slight resistance to the movement of the gases and thus maintain a substantial volume of the gases entirely across the face of the wall; in addition, the arrangement of the sizes of the openings 27 is adapted to distribute the gases practically evenly to 115 the spaces in front of the walls corresponding to the several burners. However, the provision of any wall structure of this nature may not always be essential, and when used its specific construction will simply be that best 120 125 130

adapted for the particular demands as regards checking and distributing the flow of the gases.

It will thus be seen that I have devised a practical and efficient system or method and construction for carrying out the desired objects of the invention. By the described method or process of recirculation, not only is a great economy effected in fuel consumption, but numerous other advantages are secured, among which is the greatly increased capacity obtained for the cracking units, due to the rapid increase in temperature as the flue gases are recirculated through the combustion chamber between the hot combustion gases and the highly heated refractory surfaces, resulting in a rapid exchange of heat. This leads also to a more thorough intermingling of the gases, and consequently a practically homogeneous mixture at a nearly uniform temperature. Since the initial temperatures of the gases are not so far apart as in former practices, this serves to reduce and practically eliminate the chilling effect on the combustion of the fuel, more perfect combustion results, and excessive and destructive temperature changes in the refractory surfaces are prevented; as a consequence there is not such a wide variation in the resultant temperatures; leading to hot or cold spots at the still heating surface. All this has the final result of not only increasing the output or capacity of the still units, but the quality of the product is improved due to the better control of the operation and greater uniformity of temperature of the gases entering into the still heating action.

It is equally apparent that the construction or arrangement of the system can be altered in any desired or required way to meet varying conditions of operations, and is in no sense to be limited to the details herein illustrated, and accordingly I desire to reserve the right to make all such changes or modifications which may fairly fall within the scope of the appended claims.

What I claim is:

1. Flue gas recirculating apparatus for cracking stills comprising, in combination with the furnace combustion chamber having an initial fuel combustion zone and a second heat exchange zone for the still heating surfaces, means for conducting and returning a fraction of the waste flue gases from said second zone to said combustion chamber, including separate discharge ducts communicating with said combustion chamber at opposite sides of said initial combustion zone, and partition structures on opposite sides of above and below said combustion zone in position to shield said initial combustion zone from the chilling effect of said flue gases on first entering said chamber. 50 55 60

2. Flue gas recirculating apparatus for cracking stills comprising, in combination with the furnace combustion chamber having a heat exchange zone for the still heating surfaces and an initial fuel combustion zone and also flue gas receiving compartments on opposite sides of above and below said combustion 70 zone, and a conduit for conducting a fraction of the exhaust gases from said heat exchange zone and terminating in ducts communicating with each of said flue gas receiving compartments. 75

3. Flue gas recirculating apparatus for cracking stills comprising, in combination with the furnace combustion chamber having an initial fuel combustion zone and a second heat exchange zone for the still heating surfaces, partition structures on opposite sides of said combustion zone and forming gas receiving compartments above and below said combustion zone, means for conducting a portion of the waste flue gases from said second 85 zone to said gas receiving compartments, and baffle structures for modifying the movement of said flue gases on their flow out of said compartments. 80

In witness whereof I hereunto affix my signature. 90

HARRY A. ATWATER.
